UNITED STATES PATENT OFFICE.

MIRABEAU L. BYINGTON, OF MILLEDGEVILLE, GEORGIA.

TURBINE WATER-WHEEL.

SPECIFICATION forming part of Letters Patent No. 227,880, dated May 25, 1880.

Application filed December 14, 1878.

To all whom it may concern:

Be it known that I, M. L. BYINGTON, of 5
Milledgeville, in the county of Wilkinson and
State of Georgia, have invented certain new
and useful Improvements in Turbine Water-
Wheels; and I do hereby declare that the fol-
lowing is a full, clear, and exact description
of the invention, which will enable others
skilled in the art to which it appertains to make
10 and use the same, reference being had to the
accompanying drawings, which form a part
of this specification.

Figure 1 is a side view of my improved wa-
ter-wheel, which partakes of the turbine type.
15 Fig. 2 is a horizontal section thereof; and Fig.
3 is a vertical section of the same.

Corresponding parts in the several figures
are denoted by like letters.

This invention relates to certain improve-
20 ments in water-wheels of the turbine class;
and they consist in the supporting of the wheel
below a jacket with cleated brackets or penda-
nts, within which fit arms on the wheel-shaft-
supporting piece, substantially as hereinafter
25 more fully set forth.

In the accompanying drawings, A refers to
a jacket or inclosure, and A' the wheel, which
jacket or inclosure is provided with a chute,
a, through which the water for running the
30 wheel is admitted to the latter. The bottom
of the case or jacket A is left open to permit
the inflowing water to pass into the wheel.

The wheel is arranged below the water-re-
ceiving jacket, with the open sides or entrances
35 of the buckets next to the opening in the bot-
tom of said jacket.

The shaft b of the wheel A' bears at its
lower end in a cross-piece or bridge, B, hav-
ing upwardly-projecting arms b' b', which are
confined in cleated brackets or pendants B'
40 B', fastened to the case or jacket A.

The wheel A' is provided with a series of
buckets, B² B², which radiate in a curvature
from the center of the wheel, with their dis-
charging ends widening or diverging at the 45
periphery of the wheel to cause the water to
pass out freely from the buckets and with
greater force. This increases the power and
speed of the wheel, and consequently enables
it to perform more work, or imparts greater
50 driving power to its shaft, through which the
machinery is driven.

This wheel is also extremely simple, easily
constructed, and cheap.

Having thus fully described my invention, 55
I claim and desire to secure by Letters Patent
of the United States—

The wheel, supported below the case A, pro-
vided with pendent arms, in combination with
cross-piece or bridge B, having upwardly-pro-
jecting arms b' b', arranged and confined in
the pendent arms B' B' of the case A, substan-
tially as described.

In testimony that I claim the foregoing as
my own I have hereto affixed my signature in
presence of two witnesses.

M. L. BYINGTON.
